2 Sheets-Sheet 2

Fig. 2.

Fig. 3.

Fig. 5.

A hand-drawn diagram of a bird-like shape, possibly a heron or crane, facing right. It has a large, dark eye on the left side of its head and a long, slightly downward-curving beak. The body is a simple, dark, curved line. Above the head, there is a small, irregular shape. To the left of the head, the number '16' is written vertically. To the right of the head, the number '40' is written vertically. Below the body, there is a small, dark, horizontal line.

UNITED STATES PATENT OFFICE

EMILE J. LALUMIERE, OF HAVERHILL, MASSACHUSETTS

TOY MACHINE GUN

Application filed January 9, 1930. Serial No. 419,622.

This invention relates to an improved toy machine gun characterized by certain new and refined improvements cooperating in producing a novel structural entity constituting a unique and distinctive contribution to the art.

Briefly stated, the invention comprises a leg supported stand and a superstructure swivelly mounted thereon, said superstructure embodying a casing constituting a housing for the operating mechanism and equipped with an imitation barrel.

Novelty is predicated upon the construction and arrangement of the mechanism within the casing which is especially designed for firing caps on a cap strip in an expeditious and successful manner, the arrangement being such as to insure the desired rapid fire action characteristic of a gun of this classification.

The particular details and their cooperation and association will become more readily apparent from the following description and drawings.

In the drawings:

Figure 1 is an elevational view of a gun constructed in accordance with the present invention.

Figure 2 is an enlarged longitudinal section through the major portion of the structure.

Figure 3 is an elevational view of the firing and feeding mechanism.

Figure 4 is a section on the line 4-4 of Figure 2.

Figure 5 is an end view of a duplex operating cam.

Figure 6 is a detail section on the line 6-6 of Figure 4.

Figure 7 is a detail sectional view through the swivel mounting on the stand.

Figure 8 is a bottom plan view of the head of the stand.

Figure 9 is a fragmentary plan view of the cap strip.

As seen in the drawings in Figure 1, the stand is designated by the reference character 10. The stand comprises suitable supporting legs 11 threaded at their upper ends into sockets 12 in the head plate 13. The head plate is provided with a central swiv-

elled screw 14 which serves to fasten the adjusting yoke 15 thereto. Pivottally connected to the yoke is the casing or housing 16 which is provided at its bottom with lugs 17 fastened to the arms of the yoke by bolts 18 as seen clearly in Figure 7. This provides the desirable adjustable mount for the gun.

The reference character 19 designates a removable cover plate for the casing and in this connection it will be noted that the casing is of appropriate configuration and has a suitable closing door 20 at the rear end to facilitate placement of the roll of caps. Incidentally, the caps are on a strip generally designated by the reference character 21 and the caps themselves are distinguished by the numeral 22.

A suitable bracket is provided in the housing to accommodate the roll of caps. The strip is fed through a guide tube 23 of appropriate curvature. This tube is fastened on a U-shaped bracket 24 on the interior of the housing. The numeral 25 designates a discharge neck for the used caps and 26 represents the imitation barrel.

I call attention to the fact that the left hand arm 27 of the bracket constitutes an abutment against which the impact end of the spring pressed plunger 28 strikes. This spring pressed plunger is in the nature of a strip of metal having longitudinal slot 29 formed therein as seen in Figure 2 and it is urged in one direction under the action of a coiled spring 30 and the spring is adjusted through the medium of an adjusting screw 31. These parts are associated with a guide cylinder 32 supported between the arms of the bracket.

Attached to the central portion of the cylinder and rising therefrom are supporting ears 34 for a crank 35. This crank has an arm 36 at one end which engages with the actuating pin 37 (see Figure 6) carried by the spring pressed plunger. The crank 35 functions primarily to actuate a feeding finger 38 which is of resilient nature and arranged to engage the caps successively and to feed the strips along between the impact plunger and the abutment or handle arm of the bracket, as seen in Fig. 2.

A companion retaining finger or keeper is designated by the reference character 37 and this is arranged to prevent retrograde sliding of the cap strip 21.

5 I now call attention to the reference character 38 which designates a rotatably mounted shaft having a handcrank 39 on one end located for convenient use by the operator. The inner end of the shaft is provided with 10 a duplex cam generally designated by the reference character 40 and this comprises cam elements 41 and 42 respectively arranged for successively engaging the pin 37 for actuating the plunger.

15 In practice, the roll of caps are placed on 20 the supporting bracket, inside of the housing, and the free end is passed through the tube 23 and along the top of the cylinder 30. Then the extremity is brought down between the hammer ends of the plunger 28 and the handle arm 27 as seen in Figures 2 and 3. In fact, the extremity of the cap strip is carried on through and out of the neck 25 as shown plainly in Figure 2.

25 By grasping the handcrank 29 and turning it in the proper direction, the shaft 38 will be rotated rapidly to actuate the duplex elements of the cam 40. These elements will successively engage the pin 47 on the plunger 30 and force it back against the tension of the spring 30. As the elements successively release the pin, the spring 30 comes into play and forcibly brings the hammer end of the plunger against the caps on the strip, thus 35 producing the desired explosion.

Each time the pins 37 goes back, the crank 35 is operated to in turn actuate the feeding finger 36, thus feeding the caps along in a step-by-step or successive manner. As before stated, the finger 37 prevents backward feeding or retrograde action of the strip. Thus, it will be seen that by rapidly turning the shaft 38, the duplex cam will actuate the pin 37 and in turn actuate the plunger and 45 fire the caps in rapid succession simulating machine guns when firing.

A careful consideration of the description, in connection with the drawings, will enable the reader to obtain a clear understanding of 50 the construction, the assembly, and the features and advantages as well as the operation. Therefore, a more lengthy description is regarded as unnecessary.

Minor changes in shape, size and materials, 55 and rearrangement of details coming within the field of invention claimed may be resorted to in actual practice if desired.

I claim:

1. In a toy of the class described, a casing, 60 a cylinder in said casing, a spring-pressed plunger in said cylinder, an impact anvil with which the hammer end of said plunger is co-operable, an actuating pin carried by said plunger, a rotatably mounted shaft, a 65 handcrank carried by one end of the shaft

located for convenient manipulation by the operator, and a duplex cam on the opposite end of the shaft located for cooperation with said pin, a crank shaft mounted on said cylinder, an operating connection between the crank shaft and said pin, and a feeding finger carried by the crank portion of said crank shaft and located for cooperation with a strip of caps for successively feeding the caps between the hammer end of the plunger and said anvil.

2. In a toy machine gun of the class described, a housing, means in said housing for accommodating a roll of explosive caps, an U-shaped bracket mounted in said housing, one of the arms thereof constituting an impact anvil, a cap guide tube carried by said bracket, a cylinder mounted between the arms of said bracket and having a longitudinal slot formed in the opposite side thereof, a spring pressed impact plunger arranged in said cylinder, and having a slot in registry with the slots of said cylinder, the hammer end of said plunger being arranged for cooperation with said anvil a rotary shaft mounted in said housing, a hand crank on one end of the shaft located for convenient operation by the operator, and a duplex cam on the opposite end of the shaft, together with an actuating pin carried by said plunger and arranged for cooperation with the elements of said cam.

In testimony whereof I affix my signature.
EMILE J. LALUMIERE.
